UNITED STATES PATENT OFFICE.

FREDERICK A. KOLB, OF NEWARK, NEW JERSEY.

DESIGN FOR LEATHER OR SIMILAR ARTICLE OF MANUFACTURE.

Application filed December 24, 1923. Serial No. 8,143. Term of patent 7 years.

To all whom it may concern:

Be it known that I, FREDERICK A. KOLB, a similar article of manufacture, illustrating citizen of the United States, and a resident of Newark, in the county of Essex and State of New Jersey, have invented a new, original, and ornamental Design for Leather or Similar Article of Manufacture, of which the following is a specification, reference being had to the accompanying drawing, forming part thereof.

The figure shows a piece of leather or similar article of manufacture, illustrating my new design.

I claim:

The ornamental design for leather or similar article of manufacture, as shown and described.

FREDERICK A. KOLB.
